UNITED STATES PATENT OFFICE.

GEORGE A. MACKER, OF WESTBOROUGH, MASSACHUSETTS, ASSIGNOR TO
THE LOCOMOBILE COMPANY OF AMERICA, OF NEW YORK, N. Y.

DESIGN FOR A TOOL-CARRIER FOR VEHICLES.

SPECIFICATION forming part of Design No. 33,081, dated August 14, 1900.

Application filed June 21, 1900. Serial No. 21,111. Term of patent 14 years.

To all whom it may concern:

Be it known that I, GEORGE A. MACKER, of Westborough, in the county of Worcester and State of Massachusetts, have invented and produced a certain new and original Design for a Tool-Carrier for Vehicles, of which the following is a specification, reference being had to the accompanying drawings, forming a part thereof, in which—

substantially parallel, while its side edges 4 4 are inclined at a slight angle to the perpendicular and convergent downwardly. Upon the face of the apron 1 are outlined an irregular series of forms 5, 6, 7, 8, 9, 10, 11, and 12, arranged as shown, and each raised from the body or plane of the apron. 20

I claim—

The design for a tool-carrier for vehicles, 25 substantially as herein shown and described.

In testimony whereof I have affixed my signature in presence of two witnesses.

GEORGE A. MACKER.

Witnesses:

FANNIE H. BULLARD,
ADAMS F. BROWN.

10 Figure 1 represents a front elevation of a tool-carrier embodying my design. Fig. 2 represents a section on line 2 2 of Fig. 1.

15 This design relates to tool-carriers for motor-vehicles, and its distinguishing feature is a flat apron 1 of greater length than height and having its upper and lower edges 2 3
